SHOE CONDITIONER

George H. De Long and Blair Dreisbach,
Allentown, Pa.

Application November 30, 1945, Serial No. 631,905

6 Claims. (Cl. 12—128)

1

Low shoes, more particularly women's pumps and oxfords, tend when being worn to bulge or gape along the upper edges of the sides between the heel and the vamp and in consequence ultimately take a permanent outward bulge which renders them unsightly as well as uncomfortable and enhances the tendency to slip at the heel. Ordinary shoe trees inserted in the shoes when not in use are not effective to bring the sides back to their original condition, and it is therefore a principal object of our invention to provide means for overcoming this bulging or gaping in a convenient and effective way through the provision of a novel device which when applied to the shoe after wearing is operative to return the bulged-out sides to their original condition and maintain them therein until any temporary "set" is eliminated and the shoe again substantially conforms to its shape when new.

A further object of the invention is the provision of means of the character aforesaid which are of extremely simple construction and can be applied to the shoe with a minimum of time and effort and as readily removed therefrom; which tend to narrow the normal width of the opening proximate the heel and thereby constantly assure a snug fit at that point which is of particular advantage in cases in which the wearer's heel is more slender than usual; which are of sightly appearance when associated with the shoe and are eminently satisfactory for their intended purpose.

Other objects, advantages and novel features of design, construction and arrangement comprehended by the invention are hereinafter more particularly pointed out or will be apparent to those skilled in the art from the following description of certain embodiments of the invention as illustrated in the accompanying drawing, in which:

Fig. 1 is a perspective view of a preferred form of our shoe conditioner as it appears when in open position preparatory to application to a shoe;

Fig. 2 is a perspective view of a conventional woman's pump with our shoe conditioner in operative position thereon; and

Fig. 3, generally corresponding to Fig. 1, is a perspective view of a modified form of the invention.

Referring first to Figs. 1 and 2, it will be apparent the device therein shown is preferably made from a single piece of suitable resilient sheet material such as metal or plastic composition or other material of generally corresponding char-

2

acteristics by first cutting or stamping it out to the proper outline from the flat sheet and then suitably forming it up to its ultimate shape. When so formed up it comprises a substantially rectangular sole 1 of sufficient length to span the shoe sole proximate the front face of the heel, and wings 2, 3 rising from the opposite ends thereof; for convenience of description the device will herein be referred to as if positioned with the sole 1 substantially horizontal and the edges *a* and *b* respectively constituting its front and rear boundaries.

Each wing from its point of junction with the sole extends angularly outward for a short distance, thence angularly inward for approximately twice the length of the outwardly directed portion, and thence vertically upward for a short distance substantially normal to the plane of sole 1. Each wing thus comprises a lower portion 4, an intermediate portion 5 and a terminal portion 6, and in the form of the invention now being described the upper extremity of one wing, for example 2, is extended and then turned substantially parallel to the sole as at 7 and bent over and under at its free edge to form a hook 8, while the free extremity of the other wing is turned outwardly to provide a narrow flange 9 engageable in said hook whereby the two wings after being sufficiently manually pressed toward each other in opposition to their natural tendency to spring apart may be locked together by engaging the hook over the flange as shown in Fig. 2 so as to secure the conditioner snugly about the body of the shoe with the sole 1 resting against the shoe sole slightly in advance of the front face of the heel and the wings, especially in their upper portions, exerting oppositely inwardly directed pressure on its sides.

The lower part of each wing proximate its juncture with sole 1 is substantially the width of the latter but at about the point at which the wing commences to incline inwardly its edges begin to diverge, the front edge *c* being carried upwardly and rearwardly in a somewhat steeper curve than the rear edge *d* with the result that the upper extremity of the front edge of each wing lies a little behind the rear edge of the sole and the upper extremity of its rear edge lies a material distance behind it whereby the upper parts of the wings are rearwardly offset with respect to sole 1 and when the conditioner is in operative position on the shoe the rear edges of the wings are quite closely adjacent the rear ends of its sides from which point they extend forwardly along and down the sides for a rel-

atively considerable distance, again as shown in Fig. 2. In consequence the inward pressure exerted on the sides by the wings is distributed for a relatively considerable distance from a point a little in front of the apex of the heel and thus in the area where the gaping tendency is most greatly concentrated whereby the effectiveness of the device in restoring the shoe to its original contour is materially enhanced. Therefore, we regard the particular conformation of the wings in their upper portions as an important feature of the invention since, as stated, the said pressure is thereby exerted and distributed principally in the zone or area which suffers the greatest deformation when the shoe is in use.

Moreover, to enhance the capacity of the device to properly position the sides of the shoe and insure their narrowing toward the heel, part 1 carrying hook 8 is preferably tapered rearwardly to substantially conform in planary outline to a narrow symmetrical trapezoid, whereby when the device is in operative position the upper parts of the wings are held in closer proximity at their rear than at their forward edges and the upper parts of the shoe sides proximate its heel are thus brought quite closely adjacent and from this point then can slightly diverge forwardly between the wings in accordance with the original conformation of the shoe.

It is believed from the foregoing that the method of attachment and operation of the device will be readily understood without extended description, but in brief it may be pointed out that whenever flange 9 is disengaged from hook 8 the wings spring apart through their natural resiliency and the device thus assumes substantially the position of Fig. 1 in which it may be readily slipped over the shoe until the sole 1 is brought relatively close to its heel. The wings 40 are then pressed oppositely inward against the sides of the shoe until the hook can be reengaged over the flange, thus locating the device in operative position as shown in Fig. 2 in which it preferably is allowed to remain until it be desired to again wear the shoe when it can be as readily detached therefrom. For best results it is desirable the device be placed on the shoe immediately after the latter has been in use for the material of which it is made is then warm, soft and pliable so it can be readily returned by the operation of the device to its original shape in which it then gradually cools and dries. Moreover, the device may be used in combination with an ordinary shoe tree if desired provided, of course, the tree is not of the kind to interfere with its application; the trees comprising separate toe and heel pieces connected by a metal spring and customarily used in women's shoes are not of this character and so are well adapted for the purpose.

In Fig. 3 is shown a slightly modified form of the invention in which both wings are provided at their upper extremities with outturned flanges 10 of generally similar character to flange 9 already described and which are adapted to cooperate with a rearwardly tapered slide 11 having hooks 12 at its lateral edges and, like part 1, approximating in planary outline a symmetrical trapezoid. Thus after the shoe is slipped between the wing portions, the sole 1 brought to proper relation with the heel of the shoe and the wings inwardly compressed, the slide may be pushed forward along flanges 10 to respectively engage them with hooks 12 and thereby hold the

wings snugly against the sides of the shoe in the same relative position as in Fig. 2.

It will now be apparent that our invention provides a simple yet efficient means of negativing the tendency of women's pumps, oxfords and other types of shoes to assume a permanent bulged or gaped condition through progressive displacement of their sides when they are in use, whereby through its employment the shoes may be caused to maintain their original trim and attractive appearance substantially throughout their life, while continued use of the conditioner is additionally effective to gradually permanently snug in the sides of the shoe adjacent the heel and thereby decrease any tendency to slip which the shoe may have originally possessed, so that frequently an improved fit is ultimately obtained especially in the case of persons whose heels are abnormally slender. Moreover because of its simple character, the invention can be sold at a relatively low price so that an individual owning several pairs of shoes can readily purchase a sufficient number to constantly keep all of them in condition.

While we have herein illustrated and described certain forms of our invention with considerable particularity we do not thereby desire or intend to restrict or confine ourselves specifically thereto as if desired changes and modifications may be made in their details of design, construction and arrangement without departing from the spirit and scope of the invention as defined in the appended claims.

Having thus described our invention, we claim and desire to protect by Letters Patent of the United States:

1. A device of the class described formed of resilient material and comprising a sole portion adapted to register with and span the sole of a shoe proximate the front face of its heel, wings rising from the ends of the sole portion having upwardly diverging and rearwardly curving edges whereby the extremities of the wings are wider than and located rearwardly of the rear edge of the sole portion, and means operable to hold said extremities in predetermined spaced relation.

2. A device of the class described formed of resilient material and comprising a sole portion adapted to register with and span the sole of a shoe proximate the front face of its heel, wings rising from the ends of the sole portion having upwardly diverging and rearwardly curving edges whereby the extremities of the wings are wider than and located rearwardly of the rear edge of the sole portion, and means operable to hold said extremities in predetermined spaced relation with their front edges laterally separated for a greater distance than their rear edges.

3. A device of the class described formed of resilient material and comprising a substantially rectangular sole portion adapted to engage and span the sole of a shoe proximate the front face of its heel, a wing rising from each end of the sole having its lower portion outwardly directed, its intermediate portion inwardly directed, and its upper portion substantially normal to the sole, and means operable to hold said upper portions in spaced relation against the natural outward bias of the wings.

4. A device of the class described formed of resilient material and comprising a substantially rectangular sole portion adapted to engage and span the sole of a shoe proximate the front face of its heel, a wing rising from each end of the sole having its lower portion outwardly directed, its

intermediate portion inwardly directed and its upper portion substantially normal to the sole, and means operable to hold said upper portions in spaced relation against the natural outward bias of the wings, including a flange on the extremity of one wing and a rearwardly tapering portion on the extremity of the other wing comprising a hook at its free edge adapted to receive the flange.

5. A unitary device of the class described formed of resilient sheet material and comprising a substantially rectangular sole portion adapted to engage and span the sole of a shoe in proximity to the front face of its heel, a wing rising from each end of the sole portion having an outwardly inclined portion proximate thereto, an inwardly inclined intermediate portion thereabove and a terminal portion substantially normal to the sole portion, the front and rear edges of the intermediate portion diverging upwardly and rearwardly whereby the free extremities of the wings are rearwardly offset from and of greater width than said sole portion, and means operable to hold said extremities in predetermined laterally spaced rearwardly inclined relation against their inherent outward bias comprising a trapezoidal portion on one wing extending inwardly substantially parallel to said sole por-

tion and turned over and under at its free edge to provide a hook, and an outwardly directed flange on the other wing adapted for reception in said hook.

6. A unitary device of the class described formed of resilient sheet material and comprising a substantially rectangular sole portion adapted to engage and span the sole of a shoe in proximity to the front face of its heel, a wing rising from each end of the sole portion having an outwardly inclined portion proximate thereto, an inwardly inclined intermediate portion thereabove and a terminal portion substantially normal to the sole portion, the front and rear edges of the intermediate portion diverging upwardly and rearwardly whereby the free extremities of the wings are rearwardly offset from and of greater width than said sole portion, each wing having an outwardly directed flange at its free extremity, and a slide generally trapezoidal in planary outline comprising inturned hooks at its lateral edges adapted to receive said flanges when the slide is moved thereover to thereby hold the terminal portions of the wings in oppositely rearwardly inclined laterally spaced relation.
